United States Patent

Des. 235,345
Patented June 10, 1975

235,345

HOLDER FOR BURNING INCENSE

Joseph Fields, 140—19 Linden Blvd.,
Jamaica, N.Y. 11436

Filed July 5, 1974, Ser. No. 486,107

Term of patent 14 years

Int. Cl. D31—00

U.S. Cl. D23—78

FIG. 1 is a perspective view of a holder for burning incense showing my new design;

FIG. 2 is a top plan view thereof;

FIG. 3 is a side elevational view thereof, the opposite side being identical;

FIG. 4 is a bottom plan view thereof;

FIG. 5 is a rear elevational view thereof;

FIG. 6 is a front elevational view thereof.

I claim:

The ornamental design for a holder for burning incense, substantially as shown.
